ADJUSTABLE BOX PLATE

James M. Tuten, Hopedale, Mass., assignor to
 Draper Corporation, Hopedale, Mass., a corporation of Maine

Application September 2, 1937, Serial No. 162,093

5 Claims. (Cl. 139—183)

The present invention pertains to fly shuttle looms and more particularly to shuttle boxes for such looms.

5 Looms of the type to which my invention applies commonly include a lay sword, a lay beam fixed to the front face of the sword, a shuttle box including a back plate having a shuttle guiding surface, and means for securing such plate to the lay sword and lay beam. The shuttle guiding plate must be accurately positioned relative to the lay beam, and relative to the reed, in order that the shuttle may be properly picked into and out of the shuttle box.

10 I propose to provide a loom having a lay sword, lay beam and shuttle box including a back shuttle guiding plate as aforesaid, and adjustable supporting means located at the back of the lay sword for supporting the shuttle guiding plate, whereby the supporting means shall be conveniently accessible for adjustment purposes.

15 The foregoing and other objects of the invention are accomplished in the construction illustrated on the accompanying drawing, of which:

20 Fig. 1 is a view in rear elevation of part of a lay assembly having the preferred embodiment of my invention applied thereto;

25 Fig. 2 is a view in cross-section taken approximately on line 2—2 of Fig. 1; and

30 Fig. 3 is a plan view of the construction shown on Fig. 1.

The drawing shows but part of a loom having my invention applied thereto, the parts and mechanisms not shown being of any suitable usual construction and forming no part of the present invention. The drawing shows a section of the usual lay beam 1 which is fixed to the front face of a sword 2 below the top thereof in the usual manner. The sword 2 is at the left hand side of the loom and another sword, not shown, supports the other end of the lay beam. The lay beam and lay swords reciprocate toward and from the front of the loom, which is toward the right on Fig. 2. A suitable reed 3 is carried by the lay, and at least one shuttle box is provided at each side of the loom.

45 The shuttle box shown on the drawing is the left hand box and consists of a floor 4, a front box plate 5 and a back box plate 6. The floor 4 is formed by the upper surface of the usual metal lay end, so-called, which is fixed on the lay beam 1. The front box plate 5 is fixed to the lay beam and the inner or right hand end of the back box plate is adjustably supported by the lay sword 2 in a manner to be described.

55 The back box plate 6 includes a plate 7 which

has a vertical front surface 8 for guiding the shuttle (not shown). The back box plate may also include a top shelf 9. A lug 10 on the plate 7 is preferably formed integrally with the plate and extends rearwardly, substantially horizontally, from the back of the plate. The lug 10 extends through an opening 11 in the sword 2 and is fixed to supporting means at the back of the sword. The opening 11 is appreciably larger than the lug 10, to permit adjustment of the lug 10 and box plate. The sole supporting means for the plate 7 may be that shown at the back of the sword.

The embodiment of supporting means shown includes a member 12 which is located adjacent the opening 11 and which has angularly related legs 13 and 14. The leg 13 is vertical while the leg 14 is horizontal and has an upper horizontal surface on which the rearward end of the lug 10 rests. The vertical leg 13 engages the inside of a vertical flange 15 on the lay sword and is clamped to such flange by a bolt 16. The bolt 16 passes through the leg 13 and through a vertical slot 17 in the flange 15. This bolt and slot connection permits the member 12 to be adjusted vertically, by sliding the bolt up or down in the slot, or angularly by pivoting the member about the bolt. It is noted that the bolt 16 is horizontal and extends in a direction longitudinally of the lay beam 1.

30 The lug 10 is fixed to the upper face of the leg 14 by a bolt 18. This bolt passes through a slot 19 in the lug 10 and a slot 20 in the leg 14. The slot 19 extends longitudinally of the lug, which is forwardly and rearwardly of the loom, and the slot 20 extends longitudinally of the lay, or at right angles to the slot 19. When the bolt 18 is tightened the shuttle guiding plate 7 and lug 10 are supported by the member 12 and may be adjusted therewith. Thus, angular adjustment of the member 12 about the bolt 16 will adjust the vertical inclination of the plate 7 and vertical adjustment of the member will move the plate vertically.

35 The bolt 18 and slots 19 and 20 permit adjustment of the plate 7 relative to the member 12. More specifically, when the bolt 18 is loosened the plate 7 and lug 10 may be moved horizontally forwardly or rearwardly or may be pivoted about the bolt to align the shuttle guiding surface 8 relative to the lay beam and reed. I have not shown any means for supporting the outer or left hand end of the back box plate because such means, if employed, may be of any suitable usual construction which will permit the plate 7 to be adjusted by 55

the improved supporting means above described.

The extending of the lug 10 through the opening 11 to the back of the sword permits the location of the supporting and adjusting means at a place where there is ample space and no interference with other loom parts. The supporting and adjusting devices may therefore be of the size required to provide ample strength and rigidity. Such devices are also conveniently accessible for adjustment purposes.

Having fully disclosed the preferred embodiment of my invention, I claim:

1. In a loom, the combination of a lay sword, a lay beam fixed to the front face of said sword below the top thereof, a shuttle box including a back shuttle guiding plate positioned in front of said sword above said lay beam, said plate having a lug extending rearwardly through an opening in said sword, and supporting means located at the back of the sword for supporting said lug and thereby said plate, said means being adjustable to adjust the vertical inclination of said plate.
2. In a loom, the combination of a lay sword, a lay beam fixed to the front face of said sword below the top thereof, a shuttle box including a back shuttle guiding plate positioned in front of said sword above said lay beam, said plate having a lug extending rearwardly through an opening in said sword, a supporting member located at the back of the sword and adjustably secured thereto for adjustment both vertically and angularly about a horizontal axis, and means adjustably securing said lug to said supporting member for adjustment of said lug and plate forwardly and rearwardly.
3. In a loom, the combination of a lay sword, a lay beam fixed to the front face of said sword below the top thereof, a shuttle box including a back shuttle guiding plate positioned in front of said sword above said lay beam, said plate hav-

ing an integral lug extending rearwardly through an opening in said sword, a vertically and angularly adjustable supporting member secured to the back of said sword adjacent said opening, and means for fixing said lug to said supporting member whereby said plate is supported by and adjustable with said member.

4. In a loom, the combination of a lay sword, a lay beam fixed to the front face of said sword below the top thereof, a shuttle box including a back shuttle guiding plate positioned in front of said sword above said lay beam, said plate having an integral lug extending rearwardly through an opening in said sword, a supporting member located at the back of the sword adjacent said opening, said member having a horizontal surface on which said lug rests, means securing said member to said sword for adjustment about a horizontal axis extending longitudinally of said lay beam, and means securing said lug on said surface for adjustment of said lug and plate with said member and forwardly and rearwardly relative thereto.

5. In a loom, the combination of a lay sword, a lay beam fixed to the front face of said sword below the top thereof, a shuttle box including a back shuttle guiding plate positioned in front of said sword above said lay beam, said plate having an integral lug extending rearwardly through an opening in said sword, a supporting member positioned at the back of said sword, said member having a vertical leg and a horizontal leg adjacent said opening, means securing said vertical leg to said sword for adjustment of said member both vertically and angularly about a horizontal axis extending longitudinally of the lay beam, and means securing said lug to said horizontal leg for adjustment of said lug and plate both with said member and forwardly and rearwardly relative thereto.

JAMES M. TUTEN.
